UNITED STATES PATENT OFFICE.

CHARLES J. AHRENFELDT, OF NEW YORK, N. Y.

DESIGN FOR A CUP.

SPECIFICATION forming part of Design No. 24,198, dated April 16, 1895.

Application filed November 17, 1894. Serial No. 529,189. Term of patent 7 years.

To all whom it may concern:

Be it known that I, CHARLES J. AHRENFELDT, a citizen of the United States, residing in the city of New York, county and State of New York, have invented and produced a new and original Design for a Cup, of which the following is a specification.

The accompanying drawing represents a cup embodying my design and consists of one figure which is a perspective view of said cup with the ornamentation displayed upon it in relief, and showing the trefoil shape of the cup at the top.

The essential feature of my design consists of a cup provided with a combination arabesque and escaloed ornamentation as shown in the accompanying drawing.

In the figure, A is the escaloed ornamentation, B is the arabesque ornamentation, C. is the lip of the cup, D D D are the greater segmental lines or indentations, and E is the handle.

The escaloed ornamentation A has a double edge which extends in a wave line around the perimeter of the cup an equal distance from the lip. It is segmented by the greater indentations which extend over the

entire cup at equal distances around its circumference, and, by lesser segmental lines D', D' which are gradually merged in the surface of the cup near the bottom. The lines running from the edge of the ornament toward the bottom of the cup are convergent. The arabesque ornamentation B is situated between the escaloed and the edge or lip of the cup, and is scroll-like in form. It is slightly scalloped on one side near the lip of the cup, and terminates in tendril-like ends near the edge of the lower escaloed. The cup is provided with one of these ornamentations for each of the three segments into which it is divided by the indentations D D D.

The handle E is provided with a composite arabesque and escaloed ornamentation similar to the one on the side of the cup and its lower end is twisted laterally where it joins the cup.

What I claim is—

The design for a cup substantially as herein shown and described.

CHARLES J. AHRENFELDT.
